CLAIM

The ornamental design for a flexible urinary drainage container, substantially as shown and described.

DESCRIPTION

FIG. 1 is a front elevation view of a flexible urinary drainage container, showing our new design.

FIG. 2 is a top plan view of the container of FIG. 1, FIG. 3 is an end elevation view of the container of FIG. 1,

FIG. 4 is a bottom plan view of the container of FIG. 1; and

FIG. 5 is a rear elevation view of the container of FIG. 1.
